UNITED STATES PATENT OFFICE.

ROSE HENOCHE, OF CHICAGO, ILLINOIS.

SANITARY RECEPTACLE.

Application filed March 17, 1927. Serial No. 176,014.

My invention relates to improvements in sanitary receptacles, being more particularly concerned with devices which are adapted to be inserted in the receptacle to support therein a destructible envelope which is to receive and enclose the refuse placed therein, so that the envelope may be removed with the refuse, thereby eliminating the possibility of soiling the receptacle and the necessity for cleansing or sterilizing the same.

One of the objects of my invention is the provision of such a sanitary receptacle for receiving refuse which may be removed without soiling or otherwise staining the receptacle.

Another of the objects of my invention is the provision of a device for conveying refuse, which is capable of folding the envelope about the refuse to facilitate the removal of the same from the receptacle.

Another object of my invention is the provision of such a device having means to discharge the refuse and envelope from the same automatically.

Other objects and advantages of my invention will appear more fully from the following description and from the accompanying drawings in which similar characters of reference indicate similar parts throughout the several views.

Referring to the drawings

Figure 1 is a view in perspective of the conveying device employed in my sanitary receptacle, in open position.

Figure 2 is a similar view of the same device in closed or folded position.

Figure 3 is a similar view of the same device in discharging position.

Figure 4 is an elevational view in cross section of my conveying device in a sanitary receptacle.

Figure 5 is a detailed plan view showing a cross section of certain actuating mechanism.

Figure 6 is a detailed elevational view of the actuating mechanism for the discharging closures.

Figure 7 is a detailed elevational view taken on the line 6-6 of Figure 6, and

Figure 8 is a rear view of a portion of the actuating mechanism.

Referring to Figures 1 to 5, 10 indicates in its entirety the conveying device which is employed in my sanitary receptacle and it may consist of an open framework 11,

preferably formed in the shape of a flat supporting ring having a projecting plate 12 of substantially rectangular shape for the purpose of supporting the actuating mechanism. The ring 11 with the plate 12 may be stamped or otherwise formed of sheet metal, and this frame as well as all of the parts of my conveying device, is preferably constructed of brass or some non-corroding metal such as aluminum.

Supported upon the flange 12 is a channelled standard 13 having a substantially U cross section extending at right angles to the plate 12 and being provided with a rearwardly projecting flange 14 at its base for attachment to the plate 12. The flanged foot 14 may be provided with a bore on each side as at 15 and the plate 12 may be provided with a threaded aperture 16 adapted to register with the bore 15. The flange 14 may be provided with a dove-tailed slot 16 in its rear edge to receive the complementary dove-tailed foot 18 of the bracket 19 which projects upward at right angles from the flange 14 between the bores 15.

The plate 12 supports a pair of upright journals 20, consisting of substantially cylindrical members having a noncircular base 21 and a reduced threaded portion 22 which may pass through the bore 15 and be threaded in the aperture 16 of the plate 12 to clamp the plate 12 and flanged foot 14 in fixed relation.

Rotatably supported within the journals 20 are the shafts 23 which are keyed to the pinions 24 supported upon the upper end of the shaft and the lower end of the shafts 23 are provided with a non-circular portion 25 which is adapted to be received in a similar aperture of a substantially semi-circular closure member 26, the shaft being provided with a screw bolt 27 to clamp the shaft and closure member in fixed relation to rotate together.

The closure member 26 may consist of substantially semi-circular sheet metal members bounded by downwardly turned flanges 64 for the purpose of providing a level base for the support of the whole device. The bracket 19 is provided with a substantially rectangular slide groove 65 which is adapted to receive a slider 28 having gear teeth upon each side in the manner of a double rack so that the teeth of the slider 28 engage with the pinions 24 and are adapted to actuate the same. The slider 28 is retained within the grooves 65 by means of a plurality of slider plates 29.

which are affixed to each side bracket 19 overlying a portion of the groove 65 so as to retain the slider 28 therein.

Integral with the slider 28, or fixed firmly thereto, is a connecting member 30 having a straight portion 31 rigidly connected with the slider 28, an offset 32, and an arm 33 parallel to the slider 28, which arm is provided with an aperture 34. The offset 32 brings the arm 33 adjacent the side of the standard 13 where the arm 33 may be provided with additional support for sliding movement in the form of a bracket 35, having a groove 36 to receive the arm 33. The bracket 35 may be fixed to the standard 13 with screws or any convenient fastening means.

The standard 13 may be extended upward a sufficient length to project out of the sanitary receptacle to be used with the conveying device and the standard 13 is provided at its upper end with a horizontal handle 37 which may be of any convenient shape for the purpose of enabling an operator to support the device in one hand. The standard 13 is provided upon the side having the arm 33 and bracket 36 with a lever 38 supported for pivotal movement upon the standard 13 by a screw post 39, and the lever 38 is provided with a reduced portion 40 of slightly smaller size than the aperture 34 in the arm 33 and projecting into said aperture. The lever 38 is also provided at its upper end with a substantially flat portion 40' for the purpose of manipulation by the thumb or other digit when the device is supported by the handle 37. It will be observed that when the lever 38 is actuated in a clockwise manner, as shown in Figure 6, the slider 28 will be actuated to the left, actuating the upper pinion (Figure 5) clockwise and the lower pinion in a counter clockwise direction. The closures 26 below the ring 11 will then be actuated by the shafts 23 to the position shown in Figure 3, opening the aperture in the middle of the ring 11 and substantially removing the floor or base from the said ring.

The ring 11 is provided with a plurality of upwardly projecting journals 41 for the purpose of pivotally supporting a plurality of folding fingers 42, normally projecting radially from the ring 11. The journals 41 may consist of the usual split blocks of metal having a bore 66 to provide a bearing for the reduced circular portion 43 of the shaft 44. The shaft 44 is provided at each end with a beveled gear pinion 45, which may be integral with the said shaft or keyed thereto, and the pinions 45 of the adjacent shafts 44 are so located as to mesh with each other and with similar pinions 46 located upon an actuating pinion 47.

The shafts 44 are each provided with a flat portion extending between the journals 41 for the purpose of fixing to each shaft a

finger 42 by means of screws 67, or any convenient fastening means. The fingers 42 consist of substantially rectangular plates of metal having their internal portions removed in order to reduce the excess weight of the device, and the fingers 42 have a slight upward curvature as shown in Figure 1, so that when in open position they extend radially from the ring 11 and slightly upward forming a framework like a shallow receptacle.

The exact number of the fingers 42 may be varied considerably, but for the usual size of sanitary receptacles, I find that the number shown is sufficient to adequately support the envelope thereon and fold the same, as will be further explained. The fingers 42 each being fixed to a shaft 44 having a pair of beveled pinions 45, it will be obvious that all of the fingers will move together when actuated by the actuating pinion 47. The actuating pinion 47 may consist of a pinion of the usual type supported between a pair of journals 41 for actuation by a rack 48, which is mounted for reciprocation within the channel of the standard 13.

The standard 13 is provided with an aperture 49 in its web beneath the handle 37 and the rack 48 is provided with a rearwardly projecting handle 50 substantially parallel to the handle 37 and projecting through the enlarged aperture 49 in such manner that the handles 37 and 50 may be pressed together by the fingers, thereby lifting the rack 48, actuating the pinion 47 and the pinions 45, as well as the fingers 42. The fingers 42 are thereby moved to the positions shown in Figures 2 and 3.

The standard 13 is provided with a plate 51 covering the upper end of the U shaped channel and enclosing the rack 48 therein for reciprocation within the channel, and in order to bias the fingers 42 to the position shown in Figure 1, I provide a spring 52 which is compressed between the upper end of the rack 48 and the handle 37 which closes the upper end of the channel.

The pinions 45, journals 41 and lower portions of the fingers 42 are preferably enclosed and covered by an annular casing member 53 consisting of a flat ring of metal having an internal annular flange 54 and a plurality of external annular flanges 55 extending over the journals 41 between each pair of fingers 42. The ring 53 is, of course, cut away sufficiently as at 56 adjacent the finger 42 to permit the desired extent of movement of these parts, and the ring 53 may be provided at its rearward edge with an upwardly projecting casing member 57 which is adapted to partially enclose the mechanism supported on the standard 13.

A complementary rear casing member 58 may be provided to fit upon the casing member 57, completely enclosing the mechanism

supported upon the plate 12 but permitting the upper end 40' of the lever 38 to project therefrom. The casing members described may be stamped of the same type of metal previously described and permanently fixed to the supporting frame of the device by screws or any convenient fastening means.

It will be observed that the two fingers 42, which are located adjacent the standard 13, are provided with extending wings 59 which are adapted to clear the casing members 57 and 58 when the fingers 42 are actuated to folding position, as shown in Figure 2, but which substantially perform the function of an additional folding finger which might be located in the position of the pinion 47.

My invention contemplates the use of envelopes or other pliable enclosing means with the conveying device 10 for the reception of refuse, and I employ the term "envelope" throughout this specification and claims in the generic sense including all types of pliable or flexible enclosing fabrics which may be used for the purpose described.

My conveying device is preferably used in combination with sanitary receptacles, and an envelope which may consist preferably of a sheet of oiled or otherwise waterproofed paper. The paper may be of a size sufficient to cover the exposed portions of the receptacle, and may be of any shape, but the rectangular form is preferred for the purpose of avoiding wastage. In order that the envelope may be conveniently folded by the fingers 42, the corners may be provided with a plurality of radially extending folds such as are usually made in the construction of boxes or other receptacles from paper.

My invention is of particular importance when applied to the sanitary receptacle 61 illustrated in Figure 4, which is provided with a central aperture 60 of sufficient size to permit the passage of the conveying device 10 when the fingers are in folded position, as shown in Figure 2, and the aperture 60 should also be of sufficient size relative to the standard 13 so that when the conveying device 10 is placed therein, as shown in Figure 4, and the handle 50 is released, the fingers 42 may open to the position shown in Figure 1, without interference with the edges of the aperture 60 or the lateral walls of the receptacle 61. The method of operation of my sanitary receptacle is as follows:

The conveying device 10 may be grasped by the handles 37 and 50, the fingers extending about the handle 50 and compressing the same toward the handle 37. The rack 48 is thereby actuated as previously described, rotating the pinion 47 as well as the pinions upon each of the fingers 42, and the fingers 42 may be moved to the position shown in Figure 2. The conveying device 10 may then be placed in the receptacle 61, and the standard 13 having been located adjacent

the rear end of the aperture 60, the handle 50 may be released and the fingers 42 opened to the position shown in Figures 1 and 4. During this time the closures 26 are, of course, in the closed position shown in Figures 1, 2 and 4.

The foldable envelope 62 is then placed within the sanitary receptacle 61 upon the shallow framework provided by the closures 26 and the radially projecting fingers 42, and the envelope 62 should preferably be of such size that it will project beyond the fingers 42, in all directions, extending below the inwardly projecting flange 63 which bounds the aperture 60 of the sanitary receptacle 61. It will thus be observed that the envelope 62 completely covers and protects all exposed portions in the interior of the sanitary receptacle 61 as well as the conveying device 10.

When it is desired to remove refuse from the sanitary receptacle 61 the operator may grasp the handle 37 and by means of the handle 50 actuate the fingers 42 to the dotted line position shown in Figure 4, whereupon the envelope 62 will be folded upward sliding from under the flange 63 of the receptacle 61 to the dotted line position shown in Figure 4. While maintaining the relative positions of the handles 37 and 50 as shown in Figure 4, the operator may lift the conveying device 10, the envelope 62 and the refuse from the receptacle 61, and convey the same safely to any desired point. The envelope and refuse may be discharged from the conveying device by actuating the exposed portion 40' of the lever 38. The closures 26, forming the base of the conveying device 10, will thereby be swung to the position shown in Figure 3, quickly removing the support from the envelope 62 and refuse therein and discharging the same without soiling the conveying device.

While the embodiment which I have chosen to illustrate shows my invention embodied in a particular type of sanitary receptacle, I desire it to be understood that my invention is not limited to this type of receptacle, and is of general application to receptacles for refuse of all kinds, such as are used in doctors' offices for receiving bandages, gauze or other refuse, wherever it is desired to eliminate cleaning of the permanent receptacle. It will thus be observed that I have invented improvements in sanitary receptacles whereby refuse may be received therein and conveyed to points desired, without soiling the same or without necessity for cleansing operations.

While I have invented and described a specific embodiment of my invention, many modifications may be made therein without departing from the spirit of the invention, and I do not wish to be limited to the precise details of the structure set forth, but desire

to avail myself of all changes within the scope of the appended claims.

Having thus described my invention, what I claim is new and desire to secure by Letters 5 Patent of the United States is:

1. In a device of the class described, the combination of an open supporting frame having an upwardly extending handle, with closure means for closing the bottom of said 10 frame to form a support, a sanitary envelope supported upon said closure means, and means extending from said frame about said closure to support the outer edges of said envelope and to fold the same upward.
- 15 2. In a device of the class described, the combination of an open supporting frame having an upwardly extending handle, with closure means for closing the bottom of said frame to form a support, a sanitary envelope 20 supported upon said closure means, means extending from said frame about said closure to support the outer edges of said envelope and to fold the same upward, and manual means for actuating said closure to 25 open position to discharge said envelope.
3. In combination with a receptacle, a water proof envelope, means for supporting said envelope in receptive position in said receptacle, means for folding said envelope 30 upon said supporting means, and means for removing said envelope and support from said receptacle.
- 35 4. In combination with a receptacle, a water proof envelope, means for supporting said envelope in receptive position in said receptacle, means for folding said envelope upon said supporting means, means for removing said envelope and support from said receptacle, and means for discharging said 40 envelope from said supporting means.
- 45 5. In a sanitary receptacle, the combination of a receptacle having an aperture in its upper surface, an overhanging flange bounding said aperture, a pliable envelope supported beneath said aperture and extending under said flange in substantially all directions, means for supporting said envelope, and manual means for removing said envelope and support from said receptacle.
- 50 6. In a sanitary receptacle, the combination of a receptacle having an aperture in its upper surface, an overhanging flange bounding said aperture, a substantially flat, destructible, water proof envelope having a 55 plurality of folds in its outer edges to fa-

cilitate folding, supported beneath said aperture and extending under said flange in substantially all directions, means for supporting said envelope, and manual means for removing said envelope and support from said receptacle.

7. In a device of the class described, an open supporting frame comprising a flat ring having a projecting plate, a plurality of closures supported on said plate for pivotal movement to close said frame, each closure being provided with a shaft and pinion, an upright standard supported on said plate, a handle upon said standard, a sliding rack engaging said pinions and a lever pivoted upon said standard and having operative connection with said rack whereby said closures may be actuated by pressing upon said lever with a digit adjacent said handle.

8. In a device of the class described, an open framework comprising a flat ring, an upright standard supported upon said ring, a handle on said standard, a plurality of journals supported in juxtaposition upon said ring, a plurality of horizontally extending pinions pivotally supported in said journals, an operating pinion journaled adjacent said standard, operative connections between said pinions and said pinion, a rack supported for sliding movement in said standard to engage said pinions, and manual means adjacent said handle to actuate said rack.

9. In a device of the class described, the combination of an open supporting frame having an upwardly extending handle, with closure means for the bottom of said frame to form a support, said closure means comprising a pair of doors pivotally mounted for sliding movement relative to said frame, a sanitary envelope supported upon said closure means, and manual means for sliding said closure means from under said envelope to discharge said envelope.

10. In combination with a receptacle, a water proof envelope, a removable supporting frame for holding said envelope in receptive position in said receptacle, and means on said frame for removing said envelope from said receptacle and discharging the same from said frame.

In witness whereof, I hereunto subscribe my name this 3rd day of March, 1927.

ROSE HENOCH.
